UNITED STATES PATENT OFFICE.

ERNEST PENBERTHY, OF REDRUTH, CORNWALL, ENGLAND, ASSIGNOR TO THE CLIMAX ROCK DRILL & ENGINEERING WORKS LIMITED, OF LONDON, ENGLAND, A COMPANY OF GREAT BRITAIN.

PERCUSSIVE ROCK DRILL.

Application filed March 24, 1927, Serial No. 178,023, and in Great Britain April 21, 1926.

This invention relates to percussive rock drills and has for its object to provide an improved form of valve for such drills.

According to the present invention the 5 valve member is provided with two spools or shoulders adapted to cooperate with ports in the cylinder of the hammer piston that after the valve has been fully moved into a position to disconnect the supply of live air to one end 10 of the hammer piston and to open the supply of live air to the other end of the hammer piston, live air is caused to act on one of the valve spools or shoulders so as to move the valve into a mid-way position so that live air 15 on its end may complete its travel until the hammer piston reaches the end of the stroke when the operation of the valve is repeated. The valve chamber may also be provided with vents so as to permit of escape of any air 20 which may leak along the valve body. The ends of the valves are adapted, in their end positions to be seated in valve bushings provided with seats circumferentially engaging with the circular portion of the valve body, 25 and with a seat against which the face of the valve body is adapted to bear.

Two forms of construction in accordance with the invention are illustrated in the accompanying drawings wherein:—

30 Figure 1 shows a longitudinal section of a percussive rock drill.

Figure 2 shows a longitudinal section of the valve.

35 Figure 3 shows a section on the line 3—3 of Figure 1 and

Figure 4 shows a longitudinal section of a modified form of valve mechanism applied to a percussive rock drill.

According to the one example of construction shown in Figures 1-3 the valve consists of a tubular body 1 having a partition 2 arranged at the centre and extending diametrically across it. On the tubular body are formed two spools or shoulders 3, 4,

45 which are adapted to co-operate with two annular grooves 5, 6, on the inner face of the valve chamber 7, and communicating with two exhaust ports 8, 9, in the cylinder 10 of the hammer piston 11 which cylinder 10 is

50 also provided with two internal annular grooves 42, 43 communicating respectively with the exhaust ports 8, 9. The tubular ends of the valve body 1 are adapted to con-

trol the supply of live air to the opposite ends of the hammer piston 11 movably mounted in the cylinder 10. The valve casing 7 is provided with ports 12, 13 which are connected by passages 14, 15 to the exhaust ports 9, 8, of the cylinder, the arrangement being such that the port 12 at the left-hand end of the valve chamber 7 communicates with the exhaust port 9 near the right-hand end of the cylinder 10, whilst the port 13 at the right-hand end of the valve chamber 7 communicates with the exhaust port 8 of the cylinder 10 near the left hand end of the latter. The valve chamber 7 is provided with an inlet port 16 for the live air, and an exhaust port 17.

The tubular ends of the valve are guided in circular members 18, 19 formed integral with end bushings 20, 21, and these circular members 18, 19 are each provided with an internal annular groove 22, 23 normally communicating with the atmosphere by means of one or more vent holes 24 so as to permit of the 60 escape of any leakage of air from opposite sides of said circular members 18, 19.

Circumferential seatings 25 and end seatings 26 for the valve are provided in the end bushings 20, 21 which are fitted into the ends of the valve casing 7, and the bushing at one end is held in position and prevented from displacement by a projection 27 formed on the division ring 28 which is located between the cylinder 10 of the hammer piston 85 and the guide 29 for the drill 30. The projection 27 of the division ring 28 when in position engages with a shoulder portion 31 on the valve bushing 20 and thus prevents any rotation thereof. The valve bushing 21 at 90 the other end of the valve chamber 7 is held in position by means of the cover plate 32 for the end of the cylinder 10 of the hammer piston which is also provided with a shouldered projection 33 adapted to engage with a corresponding shoulder 34 on the valve bushing 21.

The spools or shoulders 3, 4 on the valve body 1 may also be provided with vent holes 35.

The operation of a valve mechanism as above described is as follows:

Assuming that the hammer piston 11 is to be driven in the direction of the arrow 36 to the right-hand end of its cylinder 10 and the valve member 1 is at the right-hand end

of its chamber as shown in Figure 1 live air will pass from the inlet port 16 to the left-hand end of the valve 1 through the port 37 in the valve bushing 20 to the left-hand end 5 of the hammer piston 11. During its movement to the right the hammer piston 11 will uncover the exhaust port 8 so that live air can pass through the passage 15 to the port 13 in the valve chamber 7 to the right of the 10 right-hand collar 4, and thus move the valve to the left. When the valve has reached the middle of its movement to the left it closes the inlet port 37 to the live air to the left-hand end of the cylinder 10, and also opens 15 the port 38 for the admission of live air to the right-hand end of the hammer piston 11 thus causing the piston 11 to move to the left. During this operation the same sequence of operations will be repeated.

20 The shoulders 3, 4 on the valve control the exhaust of air from the cylinder 10 of the hammer piston. When the piston 11 has reached its left-hand position, that is at the instant when it strikes the drill steel, the 25 exhaust port 9 near the right-hand end of the cylinder 10 communicates by means of the passage 14 with the port 12 at the left-hand end of the valve chamber, and as the area of the shoulder 3 is greater than the area 30 of the end of the valve, against which the air acts when the valve is opened, the valve is moved to its mid-position, and air will pass the left-hand end of the valve and enter the left-hand end of the cylinder 10 through the 35 port 37. During this movement the right-hand shoulder 4 on the valve body will uncover the exhaust port 9 at the right hand end of the cylinder so that this will be directly connected to the main exhaust 17.

40 The small vent holes 35 provided in the spools or shoulders 3, 4 of the valve are adapted to serve to scavenge the valve chambers alternatively when pressure is applied at the opposing end through one or other of 45 the exhaust ports of the cylinder.

In a modified form of construction (Fig. 4) the valve 1 is tubular and is not provided with a partition so that in the position of the valve as shown live air passes through the 50 interior of the valve body 1 to the left-hand end of the cylinder 10 of the hammer piston, whereas when the valve is in its left-hand position the supply of live air is admitted to the right end of the cylinder, whilst the admission of the other end of the cylinder is 55 closed by the valve. In this case the spools or shoulders 3, 4 are not provided with vent holes, but vent holes 39 are provided in the circular members 18, 19 which are formed 60 integral with the valve bushings 20, 21 so as to produce the necessary scavenging. The operation of the valve is otherwise the same as that above described in connection with 65 Figures 1 to 3.

65 Having thus described our invention what

I claim as new and desire to secure by Letters Patent is:—

1. In a percussive rock drill a cylinder said cylinder having two inlet ports one at each end thereof, said cylinder having two exhaust ports spaced apart and intermediate said inlet ports, said cylinder having passages therein, one passage leading from one exhaust port to a point outside said cylinder between the second exhaust port and the inlet port nearest thereto whilst the second passage leads from the second exhaust port to a point outside said cylinder between the first exhaust port and the inlet port nearest thereto, a hammer piston working in said cylinder, said hammer piston being adapted during its operation to control the opening and closing of said exhaust ports, a valve chamber mounted on said cylinder, said valve chamber having an inlet port and an exhaust port and passages leading from the inlet port in said valve chamber to the inlet ports in said cylinder, said exhaust port in said valve chamber being adapted to be brought alternately into communication with the exhaust ports in said cylinder, and a valve member in said valve chamber, said valve member consisting of a tubular member and two spools mounted on said tubular member, said tubular member and spools being adapted to control the passages of said valve chamber and the exhaust ports of said cylinder, said valve chamber having small air vents therein.

2. In a percussive rock drill a cylinder, said cylinder having two inlet ports one at each end thereof, said cylinder having two exhaust ports spaced apart and intermediate said inlet ports, said cylinder having passages therein, one passage leading from one exhaust port to a point outside said cylinder between the second exhaust port and the inlet port nearest thereto whilst the second passage leads from the second exhaust port to a point outside said cylinder between the first exhaust port and the inlet port nearest thereto, a hammer piston working in said cylinder, said hammer piston being adapted during its operation to control the opening and closing of said exhaust ports, a valve chamber mounted on said cylinder, said valve chamber having an inlet port and an exhaust port and passages leading from the inlet port in said valve chamber to the inlet ports in said cylinder, said exhaust port in said valve chamber being adapted to be brought alternately into communication with the exhaust ports in said cylinder, and a valve member in said valve chamber, said valve member consisting of a tubular member and two spools mounted on said tubular member, said tubular member and spools being adapted to control the passages of said valve chamber and the exhaust ports of said cylinder, said valve chamber having small air vents therein for 130

scavenging the portions at the outer ends of the valve chambers alternately when pressure is applied at the opposing end through one or other of the exhaust ports of said 5 cylinder.

3. In a percussive rock drill a cylinder, said cylinder having two inlet ports one at each end thereof, said cylinder having two exhaust ports spaced apart and intermediate 10 said inlet ports, said cylinder having passages therein, one passage leading from one exhaust port to a point outside said cylinder between the second exhaust port and the inlet port nearest thereto whilst the second 15 passage leads from the second exhaust port to a point outside said cylinder between the first exhaust port and the inlet port nearest thereto, a hammer piston working in said cylinder, said hammer piston being adapted 20 during its operation to control the opening and closing of said exhaust ports, a valve chamber mounted on said cylinder, said valve chamber having an inlet port and an exhaust port and passages leading from the inlet port 25 in said valve chamber to the inlet ports in said cylinder, said exhaust port in said valve chamber being adapted to be brought alternately into communication with the exhaust ports in said cylinder, and a valve member in 30 said valve chamber, said valve member consisting of a tubular member and two spools mounted on said tubular member, said tubular member and spools being adapted to control the passages of said valve chamber and 35 the exhaust ports of said cylinder, valve bushings in said valve chamber, and circular members formed integral with said valve bushings, said valve chamber and said circular members having registering vent holes.
4. In a percussive rock drill, a cylinder having two inlet ports, one adjacent each end thereof, and two exhaust ports located between said inlet ports, a hammer piston working in said cylinder, a valve chamber 40 mounted on said cylinder, said valve chamber having one inlet port and one exhaust port and passages leading from the inlet port therein to the inlet ports in said cylinder, and a valve member mounted for to and fro movement in said valve chamber, said valve member consisting of a tubular member and two spaced spools on said tubular member, one of said spools controlling one of said cylinder exhaust ports, and the second spool controlling 45 the second cylinder exhaust port, the exhaust port in said valve chamber being located between said spools, said cylinder having two passages therein, one of said passages leading from one cylinder exhaust port to a 50 point in the valve chamber adjacent the extreme end position of the face of the spool, controlling the second cylinder exhaust port, remote from the spool controlling the first cylinder exhaust port, whilst the other passage leads from the second cylinder exhaust

port to a point in the valve chamber adjacent the extreme end position of the face of the spool, controlling the first cylinder exhaust port, remote from the spool controlling the second cylinder exhaust port, the 70 hammer piston being adapted to open and close said passages leading from the cylinder exhaust ports during the movement of said hammer piston.

5. In a percussive rock drill, a cylinder having two inlet ports, one adjacent each end thereof, and two exhaust ports located between said inlet ports, a hammer piston working in said cylinder, a valve chamber mounted on said cylinder, said valve chamber having one inlet port and one exhaust port and passages leading from the inlet port therein to the inlet ports in said cylinder, and a valve member mounted for to and fro movement in said valve chamber, said valve member consisting of a tubular member and two spaced spools mounted on said tubular member, said spools being located in the valve chamber on opposite sides of the exhaust port 75 in said valve chamber, said valve member 80 consisting of a tubular member and two spaced spools mounted on said tubular member, said spools being located in the valve chamber on opposite sides of the exhaust port in said valve chamber and being adapted to 85 control communication between the cylinder exhaust ports and the exhaust port in the valve chamber, said cylinder having annular grooves in the inner surface thereof and kicker ports in each of said grooves, said cylinder having passages leading from the kicker ports into said valve chamber, one of said passages leading from one kicker port to beyond the second kicker port and to a point in 90 said valve chamber adjacent the end position of one spool, whilst the second passage leads from the second kicker port to 95 beyond the first kicker port and to a point in said valve chamber adjacent the end position of the second spool.

6. In a percussive rock drill, a cylinder having two inlet ports, one adjacent each end thereof, and two exhaust ports located between said inlet ports, a hammer piston working in said cylinder, a valve chamber mounted on said cylinder, said valve chamber having one inlet port and one exhaust port and passages leading from the inlet port therein to the inlet ports in said cylinder, and a valve member mounted for to and fro movement in said valve chamber, said valve member consisting of a tubular member and two spaced spools mounted on said tubular member, said spools being located in the valve chamber on opposite sides of the exhaust port in said valve chamber and being adapted to control communication between the cylinder exhaust ports and the exhaust port in the valve chamber, said cylinder having annular grooves in the inner surface thereof and kicker ports in each of said grooves, said cylinder having passages leading from the kicker ports into said valve chamber, one of said passages leading from one kicker port to beyond the second kicker port and to a point in said valve chamber.

- ber adjacent the end position of one spool, whilst the second passage leads from the second kicker port to beyond the first kicker port and to a point in said valve chamber adjacent 5 the end position of the second spool, said valve chamber having annular grooves in the interior thereof, each of said grooves communicating with one of the exhaust ports in said cylinder.
- 10 7. In a percussive rock drill, a cylinder having two inlet ports, one adjacent each end thereof, and two exhaust ports located between said inlet ports, a hammer piston working in said cylinder, a valve chamber mounted 15 on said cylinder, said valve chamber having one inlet port and one exhaust port and passages leading from the inlet port therein to the inlet ports in said cylinder, and a valve member mounted for to and fro movement in said 20 valve chamber, said valve member consisting of a tubular member and two spaced spools mounted on said tubular member, said spools being located in the valve chamber on opposite sides of the exhaust port in said valve 25 chamber and being adapted to control communication between the cylinder exhaust ports and the exhaust port in the valve chamber, said cylinder having annular grooves in the inner surface thereof and kicker ports in 30 each of said grooves, said cylinder having passages leading from the kicker ports into said valve chamber, one of said passages leading from one kicker port to beyond the second kicker port and to a point in said valve 35 chamber adjacent the end position of the second spool, and valve bushings fitted in the ends of said valve chamber, said valve bushings having seats adapted to engage circumferentially with the ends of the tubular member, and seats against which the end 40 faces of the tubular member are adapted to bear.
8. In a percussive rock drill a cylinder, said cylinder having two inlet ports, one at each end thereof, and two exhaust ports spaced 45 apart and intermediate said inlet ports, said
- cylinder having two internal annular grooves, communicating one with each of said exhaust ports, and two kicker ports, one kicker port in each groove, a valve chamber mounted on said cylinder, valve bushings fitted into the ends of said valve chamber, said valve chamber having one inlet port and one exhaust port and passages leading from said inlet port, said bushings having passages 50 therein, said last mentioned passages being adapted to form communication between the first mentioned passages and the inlet ports in said cylinder, circular members formed integral with said bushings, said circular member having annular grooves therein and vent holes in communication therewith, a tubular member mounted for to and fro movement in said valve chamber, two spaced spools mounted on said tubular member, said spaced spools being located in said valve 55 chamber on opposite sides of the exhaust port in said valve chamber and adapted to seat against the circular members, whilst the tubular portions of the tubular member beyond the spools are adapted to control the 60 passages leading from the inlet port in the valve chamber to the inlet ports in said cylinder, said valve chamber having internal annular grooves communicating one with each of the exhaust ports in said cylinder, said cylinder having two passages therein, one of said passages leading from one kicker port to beyond the second kicker port and to a point adjacent the seating face of one circular member, whilst the other passage leads 65 from the second kicker port to beyond the first kicker port and to a point adjacent the seating of the second circular member, and a hammer piston working in said cylinder, the arrangement being such that the hammer 70 piston exposes the kicker ports for the purpose of enabling the valve member to be actuated whilst the valve member when actuated controls the passages leading to the inlet ports of said cylinders and said valve member also controlling the exhaust ports of 75 said cylinder and a diametral partition in said tubular member in a position mid-way between said spools.

ERNEST PENBERTHY.
